TOOL AND EXTRACTOR

Frank Joseph Ross, Detroit, Mich.

Application May 25, 1933, Serial No. 672,791

3 Claims. (Cl. 164—124)

This invention relates to tools and tool retainers, and particularly to interchangeable or removable punching, drilling and cutting tools, especially those having shank portions adapted to be held in a retainer, chuck or collet, while the working portion of the tool projects therefrom.

Interchangeable punches and dies are particularly benefited by the application of my invention thereto, particularly when held in retainers of the so-called interchangeable type, and an important object of the invention is the provision of means whereby interchangeable punches may be removed and replaced, even though broken, from places in which they would ordinarily be inaccessible and it would be necessary to partially dismantle the punch press or other machine to effect removal and replacement of a broken tool.

A further object is the provision of means whereby a broken punch mounted in an interchangeable retainer carried by the punch holder of a punch press may easily and quickly be removed from the retainer and a new one inserted without disturbing the stripper plate or dismantling other portions of the machine, even though an installed punch is partially or entirely screened or rendered inaccessible by a stripper plate also carried by the punch holder,--which is a common construction in which the punch ordinarily only projects through the stripper plate while performing a punching operation.

Another object is the provision of a shanked tool, such as a punch, having an irregular locking portion carried by its shank adapted to be engaged by an extracting and handling tool to enable the shanked tool or punch to be drawn from its socket and a new one inserted from a remote point.

Other objects and advantages will be apparent from the following description, wherein reference is made to the accompanying drawing illustrating preferred embodiments of my invention, and wherein similar reference numerals designate similar parts throughout the several views.

In the drawing:

Figure 1 is a fragmentary sectional view of a combination punch press and shear constituting an illustrative machine affording a useful application of my invention, showing a punch held in an interchangeable retainer and in the process of performing work upon sheet metal stock;

Figure 2 is a partly sectional and partly side elevational view of my improved punch with the extracting and handling tool attached thereto, fragmentarily showing a stripper plate through which the tool is passed to engage the punch;

Figure 3 is a similar view of a modification; Figure 4 is a similar view of another modification, and

Figure 5 is a section taken substantially on the line 5—5 of Figure 4.

Referring now to the drawing, reference character 10 designates the bed of a punch press which carries a die plate 11, above which is vertically reciprocable a punch holder 12, the mechanism for moving which, forming no part of this invention, is not shown.

Supported by the punch holder is shown a single retainer block 14 having a punch socket 15 therein and carrying mechanism for locking and releasing at will a punch in the socket. Obviously in practise a plurality of nested punches might be used. The punch-locking and releasing mechanism may be of any desired type and construction, that shown being a popular form in which a locking detent 16 is slideable in a lateral channel into and from the punch socket, being actuated and held in position by a combined wedge and actuating cam 17 having a front face arranged at a wedging angle with relation to a similarly inclined rear face of detent 16, so that it (the wedge) may lock the detent in projected position when engaged between the rear face of the detent and the end of the channel. The wedge-cam is manipulatable by means of a plunger 18, which may, as shown, project from the retainer block; member 17 being urged toward locking position (and the detent also urged into the punch socket) by means of a spring 20. An aperture 19 in the stripper plate 25, in alignment with the plunger, permits manipulation of the latter from beneath, as by means of a rod or other suitable tool (not shown) which may be passed therethrough for the purpose.

The particular press construction shown also carries a shearing blade 22, adapted to trim the edge of the stock 23, as shown, concurrently with the punching operation, although this will be seen to be immaterial insofar as my present invention is concerned. The stripper plate 25 also carried by the punch holder is spring-mounted as by slide bolts 13 in such manner that its lower surface ordinarily projects below the end of the punch 26, while when the punch holder descends to perform a punching operation the stripper plate is forced upward, or rather held by the work as the punch continues to descend, thus compressing the spring 27 while the punch is projected through and from the clearance aperture 28 in the stripper plate. The clearance aperture is made larger than both the working portion of the punch and than its

shank portion 26; which shank portion also is larger than the working portion 26.

Upon or immediately beneath the shank portion of the punch, in any event preferably upon a portion thereof heavier than the working portion and so less likely to break, tapered threads, 30, are cut upon the outer surface. As best shown in Figure 2, the clearance between the punch and the walls of the clearance aperture in the stripper plate, is sufficient to permit not only passage of the shank of the punch therethrough, but insertion of a socket wrench, as 32, proportioned to fit therewith and to receive within itself the working portion of the punch, which may extend into the socket 33 in the body of the wrench. At its upper extremity the wrench is provided with tapered female threads 35 engageable with the complementary male threads (30) of the punch.

It will be seen that by virtue of this construction, the socket wrench may be projected through the stripper plate into engagement with the punch, and when turned to lock the wrench and punch together, may be used to pull the punch axially from its socket and through the stripper plate (after, of course, first releasing the retainer by means of plunger 18). In similar fashion, by a reverse operation, a new punch may be inserted. Whether the threads by which the wrench and tool are adapted to be locked together are of the complete screw type or the shorter bayonet type, or other equivalent interlocking cam or lug construction be used, is of course immaterial, the important consideration being that means carried by a heavier portion of the tool be provided enabling locking the wrench and tool together in a manner not interfering with axial movement of the tool and wrench through the confined space provided by the clearance aperture in the stripper plate.

As shown in the modified disclosure of Figure 3, a male wrench, as 32² may be used, and the punch, designated 26², axially drilled from its free working end, preferably into the shank, where a threaded portion, designated 30², is provided. With this threaded portion the end of the wrench is of course complementarily threaded to mesh, and it will be seen that when the wrench is screwed into engagement therewith it may be used to extract or insert a punch in a manner similar to the operation of the first described embodiment. This construction enables use of such a special punch and extracting and handling wrench where for one reason or another it is not desired to provide a sufficiently large clearance aperture in the stripper plate to permit use of the form first described, as is sometimes the case when it is desired to use the aperture in the stripper plate, or in a bushing as 28² inserted therein, as a pilot for the punch by arranging it to snugly fit the elongated shank.

Figures 4 and 5 illustrate another modification in which preferably a plurality of longitudinal grooves or "flats" as 30³ are formed in the punch shank and extending part way up the same from its lower end. Intersecting the longitudinal flats or grooves is a circumferential slot 31³. The wrench 32³ is socketed somewhat similarly to the

wrench 32 first described, to receive the lower end of the punch, and provided also with an upwardly extending portion 40 of enlarged internal diameter adapted to receive the lower end of the punch shank 26³, (below the circumferential slot 31³) which may be somewhat reduced in diameter, as shown. Carried by such upper portion 40 of the wrench are inwardly projecting interlocking lug portions 35³ proportioned to clear and slide over the flattened lower portion when turned to one position, but to fit into and interlock with the circumferential slot when partially turned from such position, to couple the wrench and punch. In the shown construction the use of four flats and complementary portions of the socket wrench results in a virtual squaring of the interlocking parts and permits locking and releasing the punch by a quarter turn of the wrench.

While it will be apparent that the illustrated embodiments of my invention herein disclosed are well calculated to adequately fulfill the objects and advantages set forth, it is to be understood that the invention is susceptible to variation, modification and change within the spirit and scope of the subjoined claims.

What I claim is:

1. In combination with a punch press including a punch holder, a punch retainer carried by the punch holder having a punch socket therein and including mechanism for quickly releasing a punch held thereby, a stripper plate also carried by the punch holder, arranged beneath the retainer and having a clearance aperture for the punch therein, said stripper plate also having an aperture therein to enable actuation from beneath of the punch releasing mechanism carried by the superiorly positioned retainer, a punch in the socket having a shank portion and a working portion, the working portion being materially smaller than the clearance aperture in the stripper plate, and a deformed portion carried by the shank of the punch adapted to be engaged by an extracting tool projected through the clearance aperture to engage the same.

2. In combination with a punch press having a reciprocable punch holder, a socketed portion carried thereby and adapted to receive a punch in the socket, releasable retaining means for holding the punch in the socket, a stripper plate carried by the punch holder apertured for passage of the punch therethrough and normally projecting below the punch, and a selectively formed locking portion carried by the punch and adapted to be engaged by a grappling tool thrust through the aperture in the stripper plate.

3. In combination with a metal forming device including a reciprocable head, a tool holder carried thereby releasable retaining means for supporting a tool in the holder, a portion of the machine projecting beneath the tool and hampering access thereto, but having an aperture therein of sufficient size to allow removal of the tool therethrough, and a selectively deformed grappling portion carried by the tool and engageable by an extracting wrench thrust through the aperture.

FRANK JOSEPH ROSS.
